UNITED STATES PATENT OFFICE

2,582,566

DISPENSING BOTTLE CLOSURE

William E. Schwimmer and Leonard Maullin,
Los Angeles, Calif.

Application March 8, 1950, Serial No. 148,438

12 Claims. (Cl. 215—73)

1

This invention relates to and has for an object the provision of a simple, economical and effective bottle closure adapted for application only to bottles having special characteristics and arranged in a novel manner so as to provide an effective seal against leakage of the fluid contents of a bottle when the closure is open and to seal the opening of the bottle against discharge of its contents when the closure is adjusted to closed position.

As distinguished from prior patented and frequently used pouring spouts and measuring dispensers which are usually arranged in the form of stoppers insertible in outlets of most all types of bottles or externally applied to the necks of bottles and in all cases readily removable, our invention contemplates the provision of a dispensing closure which when once affixed to a bottle is incapable of removal except by breaking the bottle, and to such end can only be applied to specially designed bottles. Hence, the bottle and the closure are inter-dependent.

While our closure may be readily used in connection with bottles or containers for many kinds of liquids and gases, it is particularly adapted for application to glass bottles for liquids such as liquors which are required to be broken after the original contents have been exhausted and to such end it is an object to provide a dispensing closure therefor which is capable of production at extremely low cost and is therefore a dispensable article which may be discarded when the bottles are broken and discarded and unworthy of reuse because of its cheapness in spite of its possible fitness for reuse.

An important object is to provide a bottle having a neck formed with an annular flanged lip and a closure longitudinally adjustable on the neck between closed and dispensing positions and provided with internal means for sealing the bottle opening when in closed position and for sealing the closure against leakage of the bottle contents when the closure is in open pouring position.

A further object is to provide a closure embodying means therewithin which is yieldable to permit application of the closure to a bottle but which is prevented from yielding and serves to lock the closure on the bottle when moved reversely to a predetermined extent.

Another object is to provide means in the closure for admitting air to and from the presence of the contained liquid so as not to impede the free flow of liquid in a pouring operation and so arranged that a separate air chamber is pro-

2

vided in interposition between a liquid dispensing chamber and atmosphere.

Other and more detailed objects of invention may appear as the description progresses.

5 We have shown a preferred embodiment of our invention in the accompanying drawing, in which:

Fig. 1 is a perspective view of our improved dispensing closure attached to a bottle of conventional form but having special characteristics adapting it for use in connection with our new closure;

10 Fig. 2 is a substantially full size cross sectional view of our closure mounted on the neck of a bottle and in closed position;

Fig. 3 is a similar cross sectional view of the same with the closure in open position;

15 Fig. 4 is a sectional plan on line 4—4 of Fig. 2; and

20 Fig. 5 is a fragmentary sectional view in the plane of Figs. 2 and 3, showing a combined seal and lock as when the closure is being applied to a bottle in a manner which prevents removal of the closure from a bottle.

25 As shown in Figs. 2 and 3 a closure C embodying our improvements is preferably but not necessarily of circular cross section and is formed with a skirt 10 open at its bottom and closed at its upper end by a wall 11. The lower portion of skirt 10 is internally threaded at 12 so that the closure may be screwed on to the externally threaded neck 13 of a bottle B to an extent limited by a shoulder 14.

The skirt 10 is provided with spaced internal 30 annular grooves 15 and 16 in which sealing elements 17 and 17' respectively are marginally held and between which a dispensing chamber 18 is formed for receiving fluid from bottle B through outlet passage 19, while a separate air chamber

35 20 is formed between sealing element 17 and wall 11. It will be noted that element 17 is in the form of a disc while element 17' is in the form of a ring. Both of the elements 17 and 17' are formed of sufficiently flexible material, such as mildly

40 45 soft plastic, that they may be inserted one after the other through the open end of skirt 10 and sprung into the grooves 15 and 16, respectively, and held by their inherent tension. Disc 17 has a vent 21 leading between chambers 18 and 20 and

50 55 chamber 20 has a vent 22 to atmosphere by means of which dispensing chamber 18 is open indirectly to atmosphere.

A pouring spout 23 is provided on skirt 10 at a point diametrically opposite vent 22 and has an outlet passage 24 leading from chamber 18. Pas-

sage 24 and vent 22 are preferably originally sealed by teats 25 and 26, respectively, so as to seal the bottle against atmosphere and thereby preserve the contents until time for use. Said teats may be cut away from the outer ends of the passages 22 and 24 when the bottle is initially opened.

Neck 13 has an annularly flanged lip 27 below which is a wide groove 28 in which groove the seal 17' is movable from completely closed position as shown in Fig. 2 to completely open position as shown in Fig. 3 with its inner edge always in engagement with the bottom of the groove 28, thereby preventing leakage of fluid from chamber 18 between skirt 10 and neck 13 as when the bottle is tilted in a pouring operation.

The skirt 10 is long enough so that when affixing a closure to a bottle the skirt may be screwed on to neck 13 to the extent of at least a few threads before sealing ring 17' engages the upper end of lip 27, after which the continued turning of the closure gradually deforms ring 17' upwardly as the ring is moved over the bevelled edge of lip 27. When the closure is sufficiently moved on the neck ring 17' will resume its original form at a point below lip 13 in groove 28. Hence, when the inner diameter of skirt 10 and the outer diameter of lip 27 are relatively established it will be impossible to retract the ring 17' beyond the flat plane of the lower side of the lip and the closure cannot be removed from the bottle.

It may be observed that the width of groove 28 corresponds to the distance the closure is movable on the bottle between completely open and closed positions but that it is not necessary to move the closure to its extreme outward position to dispense the contents of the bottle from chamber 18.

When the closure is adjusted inwardly to a point whereat the end of skirt 10 almost if not actually engages shoulder 14 on the neck 13 (Fig. 2), the disc 17 will seal passage 19 at the upper side of lip 27 so that fluid from the bottle cannot be evacuated into chamber 18 even though the bottle is tilted as in pouring position, and in said position the ring 17' will seal the lower joint between neck 13 and skirt 10 at the lower end of groove 28. At all times the inner edge of ring 17' seals the space between skirt 10 and the bottom of groove 28, and when the closure is completely open it seals the space between skirt 10 and lip 27 (Fig. 3).

Vents 21 and 22 to chamber 20 from chamber 18 and from chamber 20 to the atmosphere, respectively, are sufficiently spaced radially from each other and both from spout 23, that when the bottle is tilted to dispense fluid from chamber 18 the fluid from chamber 18 will not flow into chamber 20 and yet air from chamber 18 will be readily vented to and from chamber 20 to the atmosphere. Also, air is freely admitted to chamber 18, passage 19 and the bottle to permit free evacuation of the fluid at will.

Fluid in any desired quantity may be dispensed freely even if the closure is only partly open. Due to the fact that the closure body may be made of rubber, plastic or other cheap material of but one molded, extruded or stamped piece of material and the seals 17 and 17' of the same or different but softer and more compressible material, the unit cost of the closures per bottle is so minimized that when the bottles are destroyed the closures may be discarded with but insignificant loss to users which is greatly less than

losses otherwise arising from free or overgenerous dispensing of valuable liquids and freely available access thereto.

Seals 17 and 17' are sufficiently stiff that when sealed in their respective grooves 15 and 16 they will not be displaced during use of the closure and yet said elements are compressible and sufficiently deformable that when the closure is closed the seal 17 will overlie the lip 27 of the bottle for closing opening 19 against flow of liquid therethrough even though the bottle is tilted as in pouring position and seal 17' will seal the joint between the skirt 10 and neck 13 at opposite extremes of its movement by engaging the lower side of lip 27 and the lower shoulder of groove 28.

As shown in Fig. 5, as the closure is telescopically applied to neck 13 to an extent of two or three threads or until seal 17' marginally engages the bevelled edge of lip 27 and as the closure is then further screwed onto the neck, the seal 17' is deformed and expanded inwardly of the surface of skirt 10 to an extent which permits it to pass between the lip and the skirt and to a point sufficiently below the lip which will permit contraction to its normal form with its annular inner edge in sealing engagement with the bottom of groove 28. The space between lip 27 and skirt 10 is just wide enough to permit seal 17 to move therethrough over the bevelled edge of the lip but not wide enough to permit passage upwardly therethrough in the absence of a similarly bevelled lower lip surface and, therefore, prevents removal of the closure from the bottle.

Our improved closure and container combination is unique in its embodiment of the double seal (when open and closed) of the closure on the bottle; the method of applying the closure to a bottle; the irremovability of the closure when applied to a bottle and the provision of controlled means for admitting air to and for exhausting air from the dispensing chamber without employment of valves; and the absence of springs and other devices usually provided in container closures.

We claim:

1. In combination, a container having a threaded neck and an annular flanged lip around its outlet, and a closure having a skirt adapted to be screwed onto said neck and having a top wall, a sealing disc borne by said skirt in a plane spaced from said top wall for engagement with said lip to close the container outlet and subdividing the interior of the closure into an upper air chamber and a lower dispensing chamber, said dispensing chamber having an outlet through which the contents of the container may be dispensed; and a sealing ring borne by the closure yieldable to permit its movement over and to sealing position with said neck in a plane below said lip and for locking the closure on the container against removal.

2. In combination, a container having a threaded neck and an annular flanged lip around its outlet, and a closure having a skirt adapted to be screwed onto said neck and having a top wall, a sealing disc borne by said skirt in a plane spaced from said top wall for engagement with said lip to close the container outlet and subdividing the interior of the closure into an upper air chamber and a lower dispensing chamber, said dispensing chamber having an outlet through which the contents of the container may be dispensed, and a sealing ring borne by the closure

yieldable to permit its movement over and to sealing position with said neck in a plane below said lip and for locking the closure on the container against removal, said air chamber having a vent to atmosphere and a port open to the dispensing chamber, whereby air resident in the dispensing chamber is exhausted to atmosphere as the contents of the container are discharged into the dispensing chamber.

3. In combination, a container having a threaded neck and an annular flanged lip around its outlet, and a closure having a skirt adapted to be screwed onto said neck and having a top wall, a sealing disc borne by said skirt in a plane spaced from said top wall for engagement with said lip to close the container outlet and subdividing the interior of the closure into an upper air chamber and a lower dispensing chamber, said dispensing chamber having an outlet through which the contents of the container may be dispensed, and a sealing ring borne by the closure yieldable to permit its movement over and to sealing position with said neck in a plane below said lip and for locking the closure on the container against removal, said neck being formed with an annular groove below said flanged lip between which and the lower extremity of said groove said sealing ring is adapted to move as the closure is adjusted between open and closed position while the annular inner edge of the ring remains in sealing engagement with the bottom surface of said groove.

4. In combination, a container having a threaded neck and an annular flanged lip around its outlet, and a closure having a skirt adapted to be screwed onto said neck and having a top wall, a sealing disc borne by said skirt in a plane spaced from said top wall for engagement with said lip to close the container outlet and subdividing the interior of the closure into an upper air chamber and a lower dispensing chamber, said dispensing chamber having an outlet through which the contents of the container may be dispensed, and a sealing ring borne by the closure yieldable to permit its movement over and to sealing position with said neck in a plane below said lip and for locking the closure on the container against removal, the upper surface of said lip being bevelled to permit movement of said sealing ring downwardly thereover into sealing and locking position and the lower surface of said lip being flat so as to prevent movement of the sealing ring upwardly over the lip.

5. In combination, a container having a threaded neck and an annular flanged lip around its outlet, and a closure having a skirt adapted to be screwed onto said neck and having a top wall, a sealing disc borne by said skirt in a plane spaced from said top wall for engagement with said lip to close the container outlet and subdividing the interior of the closure into an upper air chamber and a lower dispensing chamber, said dispensing chamber having an outlet through which the contents of the container may be dispensed, and a sealing ring borne by the closure yieldable to permit its movement over and to sealing position with said neck in a plane below said lip and for locking the closure on the container against removal, said closure body being formed of rigid material and said sealing disc and ring being formed of compressible and resilient material and affixed at their external peripheries to the skirt of the closure.

6. In combination, a container having a threaded neck and an annular flanged lip around

its outlet, and a closure having a skirt adapted to be screwed onto said neck and having a top wall, a sealing disc borne by said skirt in a plane spaced from said top wall for engagement with said lip to close the container outlet and subdividing the interior of the closure into an upper air chamber and a lower dispensing chamber, said dispensing chamber having an outlet through which the contents of the container may be dispensed, and a sealing ring borne by the closure yieldable to permit its movement over and to sealing position with said neck in a plane below said lip and for locking the closure on the container against removal, said air chamber having a vent to atmosphere and a port open to the dispensing chamber, whereby air resident in the dispensing chamber is exhausted to atmosphere as the contents of the container are discharged into the dispensing chamber, said vent and said port being located at substantially diametrically opposite points on the closure from the closure outlet to prevent flow of liquid from the dispensing chamber into the air chamber and outwardly therefrom when the container is tilted in a pouring operation.

7. In combination, a container having a neck formed with an annular external groove the upper extremity of which is defined by a flanged lip and the lower extremity of which is defined by an annular shoulder, a closure adapted for adjustable telescopic attachment to said neck and formed with a top wall and a pouring outlet below said top wall, and an annular sealing ring borne by and movable with the closure between opposite positions of engagement with the lower surface of said lip and said shoulder while its inner edge engages the bottom of said groove, and cooperating means on the closure and said neck for axially adjusting the closure between pouring and non-pouring positions on the container in accordance with the limitations of movement of the sealing ring.

8. In combination, a container having a neck formed with an annular external groove the upper extremity of which is defined by a flanged lip and the lower extremity of which is defined by an annular shoulder, a closure adapted for adjustable telescopic attachment to said neck and formed with a top wall and a pouring outlet below said top wall, and an annular sealing ring borne by and movable with the closure between opposite positions of engagement with the lower surface of said lip and said shoulder while its inner edge engages the bottom of said groove, and cooperating means on the closure and said neck for axially adjusting the closure between pouring and non-pouring positions on the container in accordance with the limitations of movement of the sealing ring, and means on the closure for sealing the container against discharge of its contents when said sealing ring engages said shoulder.

9. In combination, a container having a neck formed with an annular external groove the upper extremity of which is defined by a flanged lip and the lower extremity of which is defined by an annular shoulder, a closure adapted for adjustable telescopic attachment to said neck and formed with a top wall and a pouring outlet below said top wall, and an annular sealing ring borne by and movable with the closure between opposite positions of engagement with the lower surface of said lip and said shoulder while its inner edge engages the bottom of said groove, and cooperating means on the closure and said neck for axially adjusting the closure between pouring

and non-pouring positions on the container in accordance with the limitations of movement of the sealing ring, and means on the closure for sealing the container against discharge of its contents when said sealing ring engages said shoulder, said means including a sealing element engageable with the lip of the container for closing the outlet of the container.

10. In combination, a container having a neck formed with an annular external groove the upper extremity of which is defined by a flanged lip and the lower extremity of which is defined by an annular shoulder, a closure adapted for adjustable telescopic attachment to said neck and formed with a top wall and a pouring outlet below said top wall, and an annular sealing ring borne by and movable with the closure between opposite positions of engagement with the lower surface of said lip and said shoulder while its inner edge engages the bottom of said groove, and cooperating means on the closure and said neck for axially adjusting the closure between pouring and non-pouring positions on the container in accordance with the limitations of movement of the sealing ring, and means on the closure for sealing the container against discharge of its contents when said sealing ring engages said shoulder, said means including a sealing element engageable with the lip of the container for closing the outlet of the container, said closure having a dispensing chamber outwardly of said lip and in communication with said pouring outlet and also in communication with the container outlet, so that when said sealing element is in open position the contents of the container may freely flow into and from the dispensing chamber through the pouring outlet for use when the container is appropriately tilted.

11. A container closure comprising: a body of hard material having a dispensing chamber and a pouring outlet therefrom and a pair of sealing elements of resilient material borne by said body in spaced planes and together movable with the closure for engagement with different surfaces of a container for respectively sealing the joint be-
